SWIMMER'S LIFE BUOY

Werner J. Lund, Staples, Minn.

Application March 18, 1948, Serial No. 15,572

1 Claim. (Cl. 9—17)

1

My present invention relates to the general class of buoys and buoyant swimming appliances, and more specifically to an improved swimmer's life buoy fashioned in form and shape of neck-yoke that it adapted to support the swimmer's head and hold the chin above the water level while the body of the swimmer is buoyed up or floated in the water in correct swimming position.

The life buoy, while adapted for comfortable and restful use by an experienced swimmer, is especially designed for use by beginners and inexperienced swimmers in supporting the head above the water and thereby enhancing the morale of the beginner. In the physical embodiment of my invention I utilize a minimum number of parts that may be manufactured with facility at low cost of production, and the parts may be assembled with convenience, to constitute a safety appliance that may be attached about the neck of the swimmer with ease, and with equal facility the life buoy may be detached and removed when desired.

The invention consists in certain novel features of construction and combinations and arrangements of parts involving the buoyant neck yoke and its detachable fastening means, as will hereinafter be described and more particularly set forth in the appended claim.

In the accompanying drawings I have illustrated a complete example of a physical embodiment of my invention in which the parts are combined and arranged in accord with one mode I have devised for the practical application of the principles of the invention. It will however be understood that changes and alterations are contemplated and may be made in these exemplifying drawings and structures, within the scope of my claim without departing from the principles of the invention.

Figure 1 is a front view showing the life buoy in position for use by a swimmer; and Figure 2 is a rear or back view of the appliance in use.

Figure 3 is a perspective view of the appliance as seen from the rear, with the fastening straps or tapes arranged in initial position for fixing the appliance in correct position.

In the preferred form of the invention shown in the drawings the life buoy or buoyant float is fashioned as a tubular, inflatable, neck yoke as A, of correct size and shape to slip over the head or around the neck of the swimmer and rest upon the shoulders, with the yoke portions 1 and 2 in Fig. 3 of reduced dimensions to comfortably fit the yoke on the shoulders of the wearer. In correct swimming posture, the medial portion of

the yoke fits snugly up and under the chin of the swimmer, to support the head, and the two adjoining ends 3 and 4 of the yoke are located at the nape of the neck.

5 The neck yoke A may be fashioned in tubular form from a fine broadcloth, rubber, rubberized material, or other material that produces an air tight and water tight structure, and the yoke may be inflated by blowing into the mouth valve 10 device 5 attached to an end of the yoke and sealed with a cap, as 6.

For a quick-detachable fastening and retaining means the yoke is provided with a pair of straps or tapes 7 and 8 having snap fasteners 9, 9 that 15 are connected with rings 10, 10, mounted by tabs 11, 11, on the respective rear ends 3 and 4 of the yoke. The free ends of the straps are passed through a complementary pair of rings 12, 12, that are supported from the front of the yoke by 20 tabs 13, 13, and it will be apparent from the drawings that these guided and retained straps are crossed in front of the chest as well as crossed at the back of the swimmer, then wrapped around the chest, and tied with a knot 14, at the 25 front, as shown in Fig. 1. With the crossed straps passing under the shoulders and around the chest, the yoke is stabilized and firmly fastened and held in position about the neck of the swimmer. In this position of the neck yoke, the head 30 of the swimmer is supported above the water, the arms are free for swimming strokes, and the beginner is relieved of the fear of sinking.

The resilient or elastic open end yokes are 35 readily adjustable about the neck of the wearer, and they may be fashioned in various sizes for children and adults, and with different buoyant capacities for use as floats.

Having thus fully described my invention, what I claim as new and desire to secure by Letters 40 Patent is:

In a safety swimming appliance, a buoyant yoke having a tubular cross-section adapted to be arranged around the neck of the user, so that the yoke lies substantially parallel to the shoulders of the user, said yoke having side portions of reduced diameter, the medial portion of said yoke being curved for fitting snugly beneath the user's chin to support the user's head, the rear ends of said yoke being spaced apart from each other, a first pair of spaced tabs extending downwardly, respectively, from the rear ends of said yoke, a ring connected to the lower end of each of said tabs, a pair of straps each having a snap fastener thereon and respectively engaging said 50 rings, a second pair of spaced tabs dependingly

carried by the medial portion of said yoke, a ring connected to the lower end of each of said second pair of tabs, said straps being adapted to be crossed in back of the user, then extended through said last-named rings, wrapped around the chest of the user, and the free ends of said straps adapted to be fastened together.
